UNITED STATES PATENT OFFICE

GEORGE WEIDNER, OF ROCHESTER, NEW YORK

PRECISION DRESSING APPARATUS FOR GRINDING WHEELS

Application filed June 28, 1929. Serial No. 374,510.

This invention relates to apparatus for dressing grinding wheels and has for its various objects:

To provide an apparatus with which the dressing operation on a grinding wheel can be done with precision.

To provide an apparatus with which a grinding wheel can be dressed to provide any desired angle thereon.

10 To provide an apparatus with which the grinding wheel can be dressed concave as well as convex.

To provide an apparatus for dressing grinding wheels in which all of the moving parts are protected from the abrasive dust liberated from the grinding wheel during the dressing operation.

15 All these and other objects of this invention will be apparent from the drawings, the specification and the appended claims forming a part thereof.

In the accompanying drawings:

Figure 1 is a side elevation of the precision dressing apparatus for grinding wheels.

20 Figure 2 is a top plan view of the apparatus.

Figure 3 is an end elevation of the apparatus with portions of it broken away in order to illustrate parts of the mechanism of 25 the apparatus in section.

Figure 4 is a horizontal sectional view of the movable diamond holder and its guide member, the section being taken on the line 4x-4x of Figure 3.

30 Figure 5 is a vertical sectional view of the diamond holder and its guide member, the section being taken on the line 5x-5x of Figure 4.

In the several figures of the drawings like 35 reference numerals indicate like parts.

The dressing apparatus forming the subject matter of this invention is especially adapted for precision work, and dresses the face of a grinding wheel angularly at any 45 desired angle and convex or concave with any desired radius.

The apparatus has a supporting base 1 which is adapted to rest on the magnet table of the grinder and is held in place thereon 50 by the magnetic force of the magnets there-

of. Gauge pins 2, 2 one near each corner of the base 1, are provided for the purpose of lining up the apparatus on the table. These pins are depressed until their lower ends project below the surface of the base and engage the edge of the table to position the base 1 with relation thereto. The center of the supporting base has a short truncated conical elevation 3 on top of which is mounted to rotate the circular turn table 4. The bottom of this turn table is provided with a depending concentric shoulder 5 and a central cylindrical pivot member 6 which project into the cylindrical depression 7 and central cylindrical hole 8 respectively to pivotally mount the turn table 4 on the supporting base 1. The turn table is held to the base by the bolt 9 which is threaded into the center of the cylindrical pivot member with its flat head 10 overhanging the bottom of the pivot member thus forming a shoulder on the pivot member which will lock the turntable to the base. In the top of the base 1 is provided the cylindrical dovetailed slot 11. This slot is concentric with the pivot member and into it extends the head 12 of the clamping screw 13. As illustrated in Figure 1 the shank of the clamping screw projects thru a hole in the turntable 4 and on top of the turntable is threaded thereto the clamping head 14. The clamping head has a handle 15 by means of which it can be turned. When the clamping head is turned, the clamping screw 13 is threaded into it and draws the turntable down onto the base and firmly clamps the turntable against rotation thereon.

Provided on top of the turn table 4 are the two bearing blocks 16 and 17 forming a trunnion bearing in which are mounted to turn the trunnion bearing pins 18 and 19 of the trunnion block 20. The trunnion pins project from each side of the trunnion block and are held in place therein by a drive fit in the block. Within the trunnion block and between the inner ends of the trunnion pins is provided a space 21 in which a pair of bevel pinions 22 and 23 are located. Of these, bevel pinion 23 is keyed to the shaft 24 which is mounted to rotate in a central bearing provided in each of the

trunnion pins 18 and 19. The hand wheel 25 is keyed to the portion of the shaft projecting from one of the trunnion pins so that the shaft 24 and with it the bevel pinion 23 may be rotated therewith. The shaft 24 is held against endwise movement in the bearings provided in the trunnion pins by the shoulder formed by the hub of the hand wheel 25 on the outside of the trunnion bearing and by the shoulder formed by the collar located at the back of the bevel pinion 23 within the trunnion block 20.

The trunnion block 20 is provided with a radial hollow boss 27 in which is anchored the reduced end of the hollow guide member 28. The portion of this guide member projecting from the boss 27 is rectangular in cross section except for the outer end thereof which is cylindrical and has a male thread provided thereon to allow the cap 30 to be threaded thereon. Centrally of the cap on the inside thereof is formed the cylindrical pocket 31 which serves as the bearing for the upper reduced end of the spindle 32. The lower end of this spindle is mounted to rotate in the lower portion of the hollow guide member 28 thru which it passes and to the end of it is threaded or otherwise suitably keyed the bevel pinion 22. A collar 33 provided intermediate of the spindle 32, in conjunction with the reduced upper end 31 of the spindle mounted to rotate in the cap 30, holds the spindle against endwise movement within the hollow guide member 28.

The thread provided on the spindle 32 is preferably square and on it is threaded the nut 34. This nut forms part of the movable holder 38 of the diamond 35 and from it projects the elongated connecting lug 36 which connects the nut with the cover plate 37 of the movable diamond holder 38. The sides of the lug are helical in order to engage the helical slot 39 provided in the cylindrical protecting sleeve 40 which surrounds the nut 34 and extends the full length of the threaded portion of the spindle 32 within the hollow guide member 28. The lug 36 also projects thru the straight guide slot 41 provided in one side of the hollow guide member 28. The engagement of the lug 36 with the straight guide slot serves to hold the nut against rotation so that when the spindle 32 is rotated the nut 34 will be threaded up or down thereon and this movement of the nut will be transmitted to the diamond holder on the outside of the hollow guide member and in turn holds the diamond holder to a straight line movement up or down thereon.

As heretofore pointed out the slot in the protecting sleeve is helical and the sides of the connecting lug 36 are helical to correspond with the sides of this slot. The protecting sleeve is free to rotate within the

hollow guide sleeve and when the nut is threaded up or down on the spindle the connecting lug, carried by it, operates to turn the protecting sleeve in either one or the other direction. As illustrated in Figure 5 the connecting lug 36 completely fills the portion of the helical slot which crosses the straight slot of the hollow guide member 28. Except for this portion of the helical slot which is closed by the connecting lug 75 the wall of the protecting sleeve closes the straight guide slot in the hollow guide member above and below the diamond holder and due to the fact that the protecting sleeve rotates as the diamond holder moves up or down, the guide slot is kept closed at all times whether the diamond holder is moving or is held stationary in any position on the hollow guide member. In this way the threaded spindle within the hollow guide 80 member is constantly protected from the abrasive dust that is cut from the grinding wheel during the dressing operation.

As illustrated in section in Figure 3 the nut 34 is grooved in the middle and in this groove on one side of the spindle 32 is located the clamping shoe 45 which is provided at the inner end of the clamping screw 46. The clamping screw passes thru a hole in the connecting lug 36 and cover plate 37 90 and has threaded thereto on the outside of the cover plate the thumb nut 47. By rotating this thumb nut in one direction the clamping screw may thus be moved to draw the clamping shoe against the inside of the protecting sleeve 40 to clamp the nut against the sleeve and prevent any further movement of the nut either up or down within the hollow guide member. A rotation of the thumb nut in the opposite direction on the other hand will release the clamping shoe and permit the movement of the diamond holder either up or down.

As illustrated in cross section in Figure 4 the diamond holder has inserted between two of its inner walls and the opposite outside walls of the guide member the bow springs 50 and 51. These bow springs have a small lug on their convex side and these lugs engage suitable holes in the wall of the diamond holder and thus anchor the springs in a predetermined position in the diamond holder so that the pressure exerted by them will keep the opposite walls of the diamond holder and the hollow guide member in frictional contact with each other and hold the diamond holder to a perfectly straight movement on the hollow guide member when traveling up or down thereon.

The diamond 35 is mounted in a suitable setting 52 which in turn is mounted in one of the sockets 53 or 54 provided on opposite sides of the diamond holder. The setting 52 of the diamond may either be threaded into the 130

socket or may be held in place therein by frictional engagement therewith.

From the description of the parts of the apparatus and their movements it will be seen that on the rotation of the hand wheel 25 the shaft 24 is rotated and with it the bevel pinion 23. The rotation of the bevel pinion 23 in turn causes the bevel pinion 22 to rotate and in doing so rotates the spindle 32 to move the diamond holder either up or down on the hollow guide member 28. The trunnion block 20 has the trunnion pins 18 and 19 fixed therein by means of a drive fit but the same pins have a running fit in the trunnion bearings 16 and 17 so that the trunnion block 20 and the guide member 28 can be swung into any angular position between the trunnion bearings. Bearing block 16 of the trunnion bearing is split on one side and a clamping screw 55 is adapted to either draw the upper half of the bearing block down onto the trunnion pin and lock this pin and with it the trunnion block against rotation in the bearing or release this pin and permit a free rotation therein to allow the pin and with it the trunnion block and guide member to swing into any desired angular position on the turn table 4.

For the purpose of turning the turn table 4 a handle 56 is provided. This handle is mounted to swing in the bifurcated lug 57 which projects radially from the turn table 4. The handle may thus be swung in either the horizontal or vertical position illustrated in the figures of the drawings. When in the horizontal position illustrated in dotted lines in Figure 1, the handle is used for turning the turn table after it has been released on the supporting base by the clamping screw 13, as above described. The handle 56 has however another function, namely that of a gauge member for setting up the apparatus with relation to the grinding wheel which is to be dressed. For this purpose the handle is swung into a vertical position as illustrated in full lines in Figure 1. In order to set the handle in a perfect vertical position the anvil 58 is provided. This anvil is mounted in the lug 59 and serves as the stop for the adjusting screw 60 carried by the handle 56. The adjusting screw is adjusted in the handle so that by bringing the end of the screw in contact with the face of the anvil 58 the handle is in a perfect vertical position on the turn table and the distance X between the middle of the guide member when in a vertical position and the outside of the handle as indicated in Figure 1 is a predetermined distance, usually three inches. The diamond may thus be located on the magnet table of the grinder with relation to the grinding wheel by measuring the distance from the wheel to the handle and then subtracting the measurement of the distance X.

As illustrated in Figure 1, the frustrated

conical elevation of the base 1 is divided into three hundred sixty degrees so that the turn table 4 can be set at any horizontal angular position on the base or be rotated in a predetermined arc by means of the handle 56 70 in order to have the diamond prescribe a corresponding arc and dress the wheel to form either a concave or convex face on the grinding wheel, depending on whether the diamond is located on one side or the other 75 of the center of rotation of the turn table.

One half of one of the sides of the trunnion block is similarly divided into one hundred eighty degrees so that this block and with it the hollow guide member and diamond holder 80 may be set in any angular position. By first setting the apparatus with relation to the grinding wheel and then giving the hollow guide member the desired angle the diamond holder is moved up and down on the guide 85 member on the rotation of the hand wheel and will dress a corresponding angle on the grinding wheel when the diamond is brought in contact with the grinding wheel.

I claim:

1. A dressing apparatus for grinding wheels comprising a base, a turn table mounted on said base, a guide member mounted to swing on said turn table, a diamond holder mounted to slide on said guide 95 member and means for moving said holder along said guide member at any angular position of said guide member.

2. A dressing apparatus for grinding wheels comprising a base, a turn table 100 mounted on said base, a trunnion bearing carried on said base, a trunnion block, a pair of trunnion pins fixed in said trunnion block and projecting from said trunnion block, said trunnion pins being mounted to turn in said trunnion bearing, a guide member projecting radially from said trunnion block, a diamond holder mounted to slide on said guide member and means located within said guide member and operated thru said trunnion bearing 105 for sliding said diamond holder on said guide member.

3. A dressing apparatus for grinding wheels comprising a base, a turn table mounted on said base, a trunnion bearing provided on said turn table, a trunnion block mounted in said trunnion bearing, a hollow guide member projecting radially from said trunnion block, a threaded spindle mounted to rotate in said hollow guide member, a diamond holder mounted to slide on the outside of said guide member, a nut threaded on said threaded spindle and means connecting said nut with said diamond holder to move said diamond holder on said guide member on the rotation of said threaded spindle.

4. A dressing apparatus for grinding wheels comprising a base, a turn table mounted on said base, a trunnion bearing provided on said turn table, a trunnion block 130

mounted in said trunnion bearing, a hollow guide member projecting radially from said trunnion block, a threaded spindle mounted to rotate in said hollow guide member, a diamond holder mounted to slide on the outside of said guide member, a nut threaded on said threaded spindle, means connecting said nut with said diamond holder to move said diamond holder on said guide member on the rotation of said threaded spindle and means operating thru said trunnion bearing and said trunnion block for rotating said spindle.

5. A dressing apparatus for grinding wheels comprising a base, a turn table mounted on said base, a trunnion bearing, a hollow guide member having a straight slot in one side of it projecting radially from said trunnion block, a protecting sleeve having a helical slot in the wall thereof mounted to 10 rotate within said hollow guide member, a threaded spindle mounted to rotate within said protecting sleeve, a bearing at the top and bottom of said hollow guide member for said threaded spindle, a nut threaded on said 15 spindle, a diamond holder mounted to slide on the outside of said hollow guide member, a lug connecting said nut with said diamond holder by passing thru the straight and helical slot of said guide member and said protecting sleeve, the movement of said lug with 20 said nut on the rotation of said spindle operating to turn said protecting sleeve to keep the straight slot in said hollow guide member covered above and below said diamond 25 holder.

6. In an apparatus for dressing grinding wheels the combination of a base, a turn table mounted on said base, a guide member mounted to swing in a vertical plane on said 30 turn table, a diamond holder mounted to slide on said guide member and means for sliding said diamond holder on said guide member.

7. In an apparatus for dressing grinding wheels the combination of a base, a turn table mounted to rotate on said base, a guide member mounted to swing in a vertical plane on said turn table, a diamond holder mounted on said guide member and a combined handle and gauge member mounted to 45 swing on said turn table and forming a handle for rotating said turn table when in a horizontal position and forming a gauge member for the location of the diamond holder with relation to the grinding wheel when in a vertical position.

8. In an apparatus for dressing grinding wheels the combination of a base, a turn table mounted to rotate on said base, a guide member mounted to swing in a vertical plane on said turn table, a diamond holder mounted on said guide member and a combined handle and gauge member mounted to swing on said turn table and forming a handle for 50 rotating said turn table when in a horizontal 55 position.

position and forming a gauge member for the location of the diamond holder with relation to the grinding wheel when in a vertical position, and adjustable means for arresting the swinging movement of said handle in one direction.

9. In an apparatus for dressing grinding wheels the combination of a base, a trunnion block, a pair of trunnion pins projecting from said trunnion block with a space provided between said pins on the inside of said trunnion block, a shaft mounted centrally of said trunnion pins and extending through the space provided between said trunnion pins, means for rotating said shaft, a bevel gear carried on said shaft and located in the space between said trunnion pins, a spindle mounted to rotate in said trunnion block and extending into the space provided between said trunnion pins, a second bevel gear carried on the end of said spindle and meshing with said first bevel gear, said spindle being threaded, a nut threaded on said spindle, a protecting sleeve surrounding said nut and said spindle, a guide member anchored in said trunnion block and surrounding said protecting sleeve, a diamond holder mounted on said guide member and means connecting said nut with said diamond holder thru said protecting sleeve and guide member to move said diamond holder on said guide member and simultaneously rotate said protecting sleeve on the rotation of said spindle by said first and second bevel pinion on the rotation of said shaft.

In testimony whereof I affix my signature.

GEORGE WEIDNER.
